UNITED STATES PATENT OFFICE.

JOSEPH A. HUGHES, OF CORPUS CHRISTI, TEXAS.

DESIGN FOR A SPOON.

SPECIFICATION forming part of Design No. 21,783, dated August 23, 1892.

Application filed May 2, 1892. Serial No. 431,572. Term of patent 3½ years.

To all whom it may concern:

Be it known that I, JOSEPH A. HUGHES, a citizen of the United States, residing at Corpus Christi, in the county of Nueces and State of Texas, have invented and produced a new and original Design for a Spoon, of which the following is a specification, reference being had to the accompanying drawing, forming part thereof.

10 The figure is a top plan view of the spoon.

The object of my invention is to provide a souvenir spoon typical or representative of the State of Texas.

15 The leading feature of my design is a head and bust of Davy Crockett, which forms the

outer and wide end of the handle, the outlines of the figure forming the margin of said handle. About the middle of the shank and projecting on each side of the same is the lone star, while on the bowl of the spoon is a representation of the old building known as the "Alamo." 20

What I claim is—

The design for a spoon, herein shown and described.

JOSEPH A. HUGHES.
